UNITED STATES PATENT OFFICE.

LUIGI FORTONI, OF LONDON, ENGLAND.

MUSIC TYPEWRITER.

Application filed October 19, 1921. Serial No. 508,852.

To all whom it may concern:

Be it known that I, LUIGI FORTONI, a subject of the King of Italy, residing at London, England, have invented new and useful Improvements in Music Typewriters, of which the following is a specification.

This invention is in the nature of an improvement upon the music type-writer for which I obtained United States Letters 10 Patent No. 1,073,976, wherein there is described a construction and arrangement of type bars carrying revoluble polygonal printing-blocks bearing musical notes, signs, or other characters, and means for operating these bars to bring the printing blocks into operation for printing on the music-paper.

According to the present invention, I dispense with these polygonal printing blocks 20 and their bars, and, in their stead, I employ polygonal printing-wheels, or discs, (hereinafter called printing-wheels) of any suitable shape, having flats or faces of equal length to correspond with the longest length 25 of the musical note, sign, or other character to be carried thereon, and I operate these wheels in the manner about to be described.

The invention further comprises certain other features which will be hereinafter referred to.

And in order that the invention may be readily understood, I will now describe it fully with reference to the accompanying drawings, wherein:

Fig. 1 is a side elevation of so much of the machine as is necessary to explain the invention, the side being broken away in order that the parts may be clearly seen.

Fig. 2 is a front view of Fig. 1.

Fig. 3 is a detail view, to a larger scale, of one of the type-levers now made use of, and certain of its associated parts.

Fig. 4 is a section of one of the type levers, taken on the line y, y , of Fig. 3.

Figs. 5 and 6 are views, to a larger scale, of a detail, and

Figs. 7 and 8 are enlarged views of two forms of the revoluble polygonal printing-wheels used.

According to the present invention, each revoluble polygonal printing-wheel a is mounted on the free end of a recessed and pivoted lever-arm b , of which there may be any suitable number, but, advantageously, I employ 40. These lever-arms being all

alike in construction and operation, it will suffice to describe one only of them.

Each lever-arm b is pivoted at a^1 in a support a^2 fixed to the frame Z of the machine, and is operated by the usual type-keys A. The revoluble polygonal printing-wheel a is operated by means of an endless chain c , lying within the lever-arm, and passing over pulleys d , d^1 of unequal size, the smaller of which d is pivoted in the free end of the lever-arm b , and carries with it the revoluble polygonal printing-wheel a . This chain is provided, in its length, with a spiral spring a^3 , to take up slack. The larger pulley d^1 carries a sprocket or toothed wheel d^2 , which meshes with a rack e , supported in a slot a^4 formed in the support a^2 , said rack being provided with a rod-like extension e^1 , both the rack and the rod being free to move in a substantially horizontal plane with the lever-arm b . The rack and rod may be arrested at any desired position, by any suitable means, so as to revolve wholly, or partially, the printing-wheel, a . Advantageously, as shown by way of example in the drawings, these means consists of a segmental or arc-shaped plate f (hereinafter called arc-shaped plate) Figs. 1 and 2, containing as many holes f^1 , as there are type-levers, there being, in the present instance, as previously stated, 40. Into each of these holes f^1 extends the threaded extremity of the rod e^1 which carries an adjustable stop e^2 (see Fig. 3). The purpose of this arc-shaped plate is to guide the rods e^1 and to limit, to any desired extent, the revolution, or partial revolution, of each of the polygonal printing-wheels. The arc-shaped plate f is supported on slides g (Fig. 2) and is moved backwards and forwards in a horizontal plane by the operation of a cranked lever k (Figs. 1 and 2) working in a quadrant l containing a number of notches k^1 (see Figs. 5 and 6), said notches corresponding in number with the number of flats or faces on the revoluble polygonal printing-wheel, one of these faces being termed the "neutral" face, because it strikes the music-paper without any revolution of the printing-wheel having taken place. Where this operation is required, the projection k^1 on the cranked lever k is engaged in the lowest or first notch l^1 in the quadrant l , this position being the "neutral" position of the cranked lever k . Hence in a machine 110

having 40 lever-arms there will be 40 "neutral" faces.

5 *p* is a chain, fixed at *q* to the lever-arm *b*, and passing over a pulley *p*², and connected by a rod *p*¹ (Fig. 3) to a cranked lever *o*, the purpose of which is hereinafter pointed out.

10 All the arms *b*, except the center one are cranked or bent at a suitable angle at their outer end (as is common in certain typewriters), so that when striking the music-paper they shall be in proper vertical position, and, further, that they shall clear one another in their movements.

15 The operation of a pivoted lever-arm when it is desired to print, is as follows: The lever *k* is set in the desired notch in the quadrant *l*, so that as the pivoted lever-arm moves upwardly, towards the paper, 20 only a certain turning movement is imparted to the revoluble printing-wheel, this turning movement being controlled by the distance between the arc-shaped plate *f*, which has been determined by the lever *k*, 25 and the adjustable stop *e*², which distance, as will be clearly seen from the drawings, depends upon the notch into which the cranked lever *k* is positioned. Thus, having set the cranked lever *k* in the required notch, 30 pressure is imparted to the type-key *A* corresponding with the character to be printed. This pressure of the type-lever *A* causes the same to move about the pivot *m*, thereby transmitting, through the medium of a link 35 *n*, (Fig. 3) a partial revolution of the crank *o*, and this imparts a pull on the rod *p*¹ and chain *p*, so causing the lever-arm *b* to rise and to assume the position shown in dotted lines in Fig. 3, and the revoluble polygonal 40 printing-wheel to strike the music-paper *B*, (carried in the carriage *C*), and so print the required note, sign, or character thereon. While the above-mentioned movements are taking place, the sprocket or toothed wheel 45 *d*² on the larger pulley *d*¹, is rotating, and moves the rack *e* in a horizontal position, provided that the lever *k* is not in the "neutral" position. But on the lever *k* being moved into any position but "neutral," and 50 the stop *e*² reaching the arc-shaped plate *f*, the larger pulley *d*¹ ceases to rotate, but because the pivoted lever-arm *b* is still rising the chain *c*, partly winds around the larger pulley *d*¹, and causes the smaller pulley *d* 55 to rotate in an anti-clockwise direction, in which direction the said pulley *d* carries with it, in its turning movement, its polygonal printing-wheel *a*, thus bringing the required face into the printing position as 60 the printing-wheel is about to strike the music-paper. Thus it is obvious that the nearer the arc-shaped plate *f* approaches to the stop *e*² a greater degree of rotation of the printing wheel will take place. This 65 stop *e*², and a set-screw *r* on the rack-

rod *e*, *e*¹, serve to adjust the printing-wheel when assembling the machine and the set-screw *r* also serves to return the printing-wheel to its normal position by coming into contact with the support *a*². 70 The return movement of the printing-wheel and of the pivoted lever-arm *b* are assisted by springs *s*, *s*¹, the latter spring being coiled around the rod *s*³, which is pivoted, at its upper end, to the pivoted lever-arm *b*, and 75 at its lower end slides freely in the support *a*².

80 Although in the drawings I have shown a hexagonal and a triangular printing wheel, it is to be understood that printing-wheels of any other polygonal form may be employed in combination with the revoluble polygonal printing-wheels, the triangular form shown in Fig. 8 being that used for carrying a long character, as for instance, a note having a long stem. It is also to be understood that there is one notch *l*² of the quadrant *l* for each face of the polygonal printing-wheels, for example, when hexagonal and triangular printing-wheels are 85 used in the same machine, there will be six notches for the hexagonal wheel, the first notch being for the neutral position, and the third and fifth notches being used for the two active faces of the triangular wheels. 90

95 Having now described my invention, what I claim is:—

1. In a music type-writer, pivoted lever-arms each provided at its outer end with a pulley carrying a revoluble polygonal printing-wheel, or disc, and at its inner end carrying a second pulley, a sprocket or toothed wheel carried by said second pulley, a driving chain passing over said pulleys and actuating the printing-wheel or disc, and means for rocking said lever-arms to bring the said printing-wheel or disc, into position for printing on the music paper, substantially as described. 100

105 2. In a music typewriter, a pivoted lever arm, printing means carried by said lever arm having a plurality of printing faces each adapted to be selectively brought into operative position, and means for selectively bringing said printing faces into operative position, said means comprising a shiftable rack rod associated with said printing means, guiding means for said rack rod, and adjustable stops associated with said rack rod and said guiding means. 110

115 3. In a music typewriter, a pivoted lever arm, printing means carried by said lever arm and having a plurality of printing faces selectively shiftable into operative position, means for rocking said lever arm to cause said printing means to make an impression, and means for selectively shifting said printing faces into operative position, said means comprising a longitudinally movable rack bar, a guiding plate for said rack 120 125 130

bar adjustable in the direction of the length of said rack bar, and means carried by said rack bar and engageable with said guiding plate.

5. 4. In a music typewriter, printing means having a plurality of printing faces each selectively shiftable into operative position, and means for shifting said printing faces into operative position, said means comprising a horizontally-movable plate and means for adjusting said plate and securing it in adjusted position, said latter means comprising a pivoted lever associated with said plate and a quadrant having notches 15 for engagement by said lever.

5. In a music typewriter, a pivoted lever arm carrying adjacent one of its ends a wheel provided with a plurality of printing faces, means for rocking said lever arm to bring one of said printing faces into contact with a sheet of paper to make an im- 20

pression upon the latter, a rotatable element associated with said lever arm, a connection between said wheel and said rotatable element to cause rotation of the former when the latter is rotated in order to bring a selected type face into operative position, movable means engaging with said rotatable element and actuated by the latter during a portion of the movement of said lever arm, 25 and adjustable means to limit the movement of said movable means and cause partial rotation of said rotatable element during further rocking movement of said lever arm. 30

In witness whereof, I have hereunto signed my name in the presence of two subscribing witnesses.

LUIGI FORTONI.
